(57) **CLAIM**

We claim the ornamental design for a pen with curved clip and angular glass tipped bottom, as shown and described.

DESCRIPTION

FIG. 1 is a front elevational view of a pen with curved clip and angular glass tipped bottom, showing our new design;
FIG. 2 is a right side elevational view;
FIG. 3 is a bottom plan view;
FIG. 4 is a rear elevational view; and,
FIG. 5 is a top plan view thereof.
